UNITED STATES PATENT OFFICE.

WILLIAM STENDER, OF MILWAUKEE, WISCONSIN.

ANNEALING-OVEN.

1,247,890.

Specification of Letters Patent. Patented Nov. 27, 1917.

Application filed March 30, 1917. Serial No. 158,502.

To all whom it may concern:

Be it known that I, WILLIAM STENDER, a citizen of the United States, and resident of Milwaukee, in the county of Milwaukee and State of Wisconsin, have invented certain new and useful Improvements in Annealing-Ovens; and I do hereby declare that the following is a full, clear, and exact description thereof.

10 My invention relates to new and useful improvements in ovens for conducting a continuous operation of annealing bottles or the like.

One important object of my invention resides in the provision of an exceedingly simple mechanism for distributing bottles on the movable bed of the oven, which mechanism is actuated by the bottles as they are fed into the oven.

20 A further object resides in the provision of a movable bed for the oven comprising a plurality of sections adapted to be successively fed into the oven and provided with detachable connecting means whereby they 25 may be moved along in the oven by a single drive member.

A still further object in connection with the detachable bed sections resides in the provision of a means for initially heating 30 said sections as they are introduced into the oven, whereby said sections are of proper temperature to receive the bottles as they are fed into the oven from the molding machine.

35 With the above and other objects and advantages in view, the invention resides more particularly in the novel combination, formation and arrangement of parts hereinafter described and pointed out in the appended claims.

In the drawings:

Figure 1 is a vertical longitudinal sectional view through the receiving end of an annealing oven constructed in accordance 45 with my invention, the general plane of this section being indicated by the line 1-1 of Fig. 2.

Fig. 2 is a transverse sectional view through the oven on the line 2-2 of Fig. 1, 50 a portion of the closing hood of the receiving end of the oven being shown in elevation.

Fig. 3 is a horizontal sectional view through the receiving end of the oven on the line 3-3 of Fig. 1, and Fig. 4 is a plan view 55 of the receiving end of the oven showing the

means for actuating the bottle distributing mechanism.

Fig. 5 is a sectional view taken on the line 5-5 of Fig. 3.

Referring now more particularly to the accompanying drawings, 5 designates each of the side walls of an elongated annealing oven, 6 designates the bottom wall thereof, and 7 designates the top wall thereof which terminates short of the side walls at the receiving end of the oven, the space between the end of the top wall and the ends of the side walls being closed by a journal plate 8 for the bottle distributing mechanism.

The bottom 6 of the oven carries a longitudinal pair of tracks 9 for the wheels 10 of a series of bed trays and each of these bed trays comprises a pair of longitudinal wheel carrying sills 11 and a plurality of transverse floor plates 12 preferably formed of sheet iron and having their edge portions bent downwardly, as shown more particularly at 13 in Fig. 1 to seat into notches of the sills 11 whereby to stiffen said plates. 30 The detachable connection of the trays is procured by lugs 14 on the rear ends of the side sills engageable in sockets 15 of the forward ends of said sills, and thus as the bed trays are moved through the oven, the 35 endmost trays may be readily connected and disconnected to afford a continuous movable bed in the oven. For procuring movement through the oven of the series of trays thus connected, each tray is provided with a central longitudinal toothed rack 16 and these racks are successively engageable with a gear 17 carried by a shaft 18 journaled in the bottom 6 of the furnace and in a bracket carried by a transverse beam 19 therebelow. 40 The racks are held in mesh with the gear by an idle pulley 20 mounted on the bottom 6 at the opposite sides of the racks.

For feeding and distributing bottles in the oven, a chute 21 is provided at one side of the feeding end of the oven and this chute may be fed in any manner procuring a positive movement of bottles thereon, a suitable conveyor, (not shown) being preferably provided to convey bottles to the chute directly from the molding machine. Journaled in the plate 8 and in the bracket of a transverse beam 22 carried by the forward ends of the side walls is a vertical shaft 23 which terminates immediately above the movable bed of the oven and which carries on its lower end a wheel 24 provided with outstanding pe-

- 2
- peripheral fingers having their ends laterally curved in the direction of rotative movement of the wheel and defining a peripheral series of consequent pockets adapted to successively receive bottles as they are forced from the chute 21, which as shown is provided with upstanding guide walls at its sides. For procuring successive rotative step movements of this wheel as bottles are supplied thereto, a wheel 25 is fixed on the shaft 23 above the top plate 8 and carries a double series of ratchet teeth, one series being engageable by a feed pawl 26 carried by a lever 27 intermediately pivoted on the shaft and having its other end in link connection with the stem 28 of a piston 29 disposed in a cylinder 30 from which a pipe 31 extends to a valve 32 disposed adjacent the discharge end of the chute, this valve being connected in turn by the pipe 33 with a suitable source of compressed air. The valve is operated by a spring urged roller carrying stem 34 projecting therefrom into the path of the bottles as they are discharged from the chute and thus as the bottles successively move from the chute, the valve will be opened to impart successive rotative steps to the wheel carrying shaft through the medium of the cylinder and piston and the pawl 26. For stopping the shaft subsequent to each rotative impulse, an arcuate pawl 35 is pivoted on the plate 8 and is resiliently urged to engagement with the other ratchet teeth of the wheel 25 by a spring urged link 26 connected therewith. The lever 27 carrying the pawl 26 is resiliently urged to initial position by a spring 37 on the piston stem 28, and air is discharged from the cylinder 30 after each actuation of the piston by any suitable means and preferably by providing the valve 32 of a two-way type normally open with respect to the cylinder, the structure of this valve being not shown, as any preferably conventional valve may be used.
- 45 Thus upon a plurality of bottles being fed into the oven, they will be disposed along the inner side of the periphery of the wheel, as shown more particularly in Fig. 3. To clear the bottles from the wheel when an arcuate series thereof has been fed into the oven, an arcuate sweep 38 is provided which normally extends transversely over the wheel, and which is carried by a vertical shaft 39 at the side of the wheel opposite the chute 21, this shaft being journaled in the top plate 8 and in the transverse beam 22. For actuating the shaft to cause an inward sweeping movement of the sweep 38, a crank-arm 40 is provided at its upper end which is in link connection with the piston stem 41 of a cylinder 42 from whence a pipe 43 extends to a valve 44 connected also with a suitable source of air pressure 45, this valve being operable by a roller carrying spring urged stem 46 which projects into the rotative path of the bottles carried by the wheel 24, and thus upon engagement of the bottles therewith procures the swinging movement of the sweep to clear the bottles from the wheel and dispose them in a substantially angular line on the movable bed, it being noted that the action of the sweep is comparatively rapid inasmuch as it must return to initial position prior to the engagement of subsequent bottles with the wheel. In view of the very slow feeding movement of the bed of the oven, the successive rotative movements of the wheel serve to retain the bottles in the pockets thereof, particularly by reason of the forward inclination of the wheel fingers with respect to their direction of travel. For returning the sweep in a rapid manner, a relatively strong spring 47 is connected with the crank-arm 40 thereof.
- 50 For closing the receiving end of the oven, a hood 48 is hinged to one side wall thereof above the movable bed trays and this hood comprises an arcuate vertical wall providing clearance for the wheel.
- 55 As the bottles are fed into the oven from the molding machine they are at a considerable heat, and to provide for a proper heating of the bed trays prior to engagement of the bottles thereon, a compartment is formed in the forward end of the furnace by the provision of a partition wall 49 below the bottom 6 of the oven and disposed in this compartment are supply coils 50 which may form part of any heating means, the bottom 6 of the oven immediately above the compartment being provided with series of apertures, and it is noted that the heating of the bed trays is facilitated by reason of the relatively thin metallic floor plates thereof. The rotation of the shaft 18 which carries the gear wheel 17 for procuring feeding movement of these bed trays is procured through the medium of a worm gear connection 52 with a countershaft 53 projecting outwardly of one of the side walls 5 and driven in any suitable manner.
- 60 While I have shown and described a preferred embodiment of my invention, it is obvious that to meet differing conditions of use, various changes and modifications of structure may be resorted to without departing in any manner from the spirit of my invention.
- 65 I claim:
1. In a device of the class described, the combination of a movable bed, a wheel mounted over said bed and provided with a series of peripheral pockets, means for feeding articles to said pockets, and a sweep member adapted to sweep articles from the pockets of the wheel, and means operable by articles carried in said pockets for actuating the sweep member.
  2. In a device of the class described the combination of a movable bed, a wheel

- mounted over the bed and provided with a series of peripheral pockets, a chute for delivering articles to the pocket, means operable by movement of said articles for im-
5 parting successive step by step rotative movement to the wheel, a sweep member adapted to sweep articles from the pockets, and means operable at the side of the wheel opposite the chute by articles in said pockets
10 for actuating said sweep member.
3. In a device of the class described, the combination of a movable bed, a wheel mounted over the bed, a vertical shaft journaled at one side of the wheel, a sweep arm upon the shaft adapted to sweep articles from the pockets of the wheel and means operable by articles in the pockets for pro-
15 curing rotation of said shaft.
4. In a device of the class described, the combination of a movable bed, a wheel mounted over the bed, a vertical shaft journaled at one side of the wheel, a sweep arm upon the shaft adapted to sweep articles from the pockets of the wheel, a crank arm on
20 the shaft, a cylinder, a piston in the cylinder connected with the crank arm, a source of motive fluid communicating with the cylinder, and a valve for controlling said fluid including a stem engageable with articles in
25 the pockets.
5. In a device of the class described, the combination of a movable bed, a journaled shaft disposed above the bed, article receiving means disposed over the bed and con-
30 nected with said shaft, means for delivering articles to said article receiving means, a ratchet wheel connected with said shaft, a pivoted lever, a pawl connected with said
35 lever and engageable with the ratchet wheel, operating means connected with said pivoted lever, means engageable by articles upon delivery to said article receiving means for actuating the operating means to advance the article carrying means, and means operable upon said ratchet wheel to prevent the operating means from advancing the article receiving means more than one step at a time, substantially as described.
6. In a device of the class described, the combination of a movable bed, a journaled shaft disposed above the bed, a wheel dis-
40 posed over the bed and connected with said shaft, article receiving means carried by said wheel, a chute for delivering articles to said article receiving means, a ratchet wheel con-
45 nected with said shaft, a pivoted lever, a bed pawl connected with one end of said lever and engaging the teeth of said ratchet wheel, a cylinder, a piston in the cylinder and con-
50 nected with said lever, a source of motive fluid communicating with the cylinder, a valve for controlling said motive fluid including a stem engageable with articles upon exit from the chute, and means operable on
55 said ratchet wheel to prevent the rotation of said article receiving wheel more than one step at a time, substantially as described.

In testimony that I claim the foregoing I have hereunto set my hand at Milwaukee,
in the county of Milwaukee and State of Wisconsin.

WILLIAM STENDER.
